UNITED STATES PATENT OFFICE.

HAROLD DUNCAN GRINNELL, OF PITTSFIELD, MASSACHUSETTS.

INDUCTION-COIL CASING.

1,117,837.

Specification of Letters Patent.

Patented Nov. 17, 1914.

Original application filed April 19, 1911, Serial No. 622,117. Divided and this application filed December 7, 1912. Serial No. 735,458.

To all whom it may concern:

Be it known that I, HAROLD D. GRINNELL, a citizen of the United States, and a resident of Pittsfield, in the county of Berkshire and State of Massachusetts, have invented a new and Improved Induction-Coil Casing, of which the following is a full, clear, and exact description, this being a division of the application for an electric gas igniter and controller, Serial No. 622,117, filed by me on April 19, 1911.

An object of the invention is to provide an improved casing for induction coils which will protect the latter completely from rain and snow.

A further object of the invention is to provide a casing which is provided with a cover which holds the coil in position without the necessity of locking means and which can be removed or replaced in a minimum of time.

Other objects and advantages will appear in the following specification and the novel features of the device will be particularly pointed out in the appended claims.

A practical embodiment of the invention is represented in the accompanying drawings forming a part of this specification, in which similar characters of reference indicate corresponding parts in all the views.

Figure 1 is a side elevation of the induction coil as applied to an electric gas igniter and controller attached to an automobile: Fig. 2 is an enlarged cross section of the same on the line 2—2 of Fig. 1; Fig. 3 is a sectional front elevation of the same on the line 3—3 of Fig. 2; Fig. 4 is a sectional plan view of the same on the line 4—4 of Fig. 3; and Fig. 5 is an enlarged transverse section of the adjustable cam for actuating the electric contact-maker, the section being on the line 5—5 of Fig. 3.

The induction coil is shown applied to an electric gas igniter and controller for a gas lamp A mounted on an automobile B and supplied with gas from a tank C by means of a hose or pipe D connected with a valve E on the tank C, the valve E controlling the outflow of the gas from the tank C to the hose D and to the burner of the lamp A. The induction coil, presently to be described in detail, is used to produce a spark on spark points located at the burner of the lamp A, with a view to ignite the gas issuing from the burner, it being, however, understood

that in the present case the ignition takes place at the time gas is flowing out of the burner with the valve E open beyond normal position, that is, beyond such open position as to furnish the gas required for a maximum even illumination. After the gas is ignited the valve E is returned to normal position and the circuit for the spark points is cut off. This result is accomplished by the use of a vibrating or induction coil F contained in a metallic casing G having a telescoping cover G' and fastened to the metal framework B' of the automobile B.

On the front lower portion of the casing G is formed a bearing G² (see Fig. 3) in which is journaled a longitudinally-extending main shaft H provided with a bevel gear wheel H' in mesh with a similar gear wheel I' secured on a shaft I provided with a hand wheel I² within convenient reach of the operator in charge of the automobile B so that the operator can readily turn the shaft I and consequently the main shaft H. The rear end of the main shaft H is connected by a link H² with the stem of the valve E so that when the shaft H is rotated by the operator turning the hand wheel I² then the valve E is opened and closed according to the direction in which the hand wheel I² is turned by the operator. The gear wheels H' and I' and the outer portion of the shaft H are inclosed in a casing J provided with a hub J' through which extends loosely the shaft H, the inner end of the hub J' abutting against one face of the gear wheel H' while the outer face of the said gear wheel is engaged by a head J² forming part of the casing J, as shown in Fig. 3. On the casing J is secured a guide J³ provided with a tube J⁴ and through the guide J³ and tube J⁴ extends the shaft I. On the tube J⁴ is loosely mounted a sleeve K connected by a pivot K' with a bracket K² attached to the framework B' of the automobile B, as plainly indicated in Fig. 2. By the arrangement described the shaft J can be moved into the desired inclined position so as to bring the hand wheel I² within convenient reach of the operator in charge of the automobile.

On the shaft H is mounted to turn loosely a member L having a shoulder L', and containing a worm L² in mesh with a worm wheel L³ attached to the main shaft H so that when the latter is rotated the member

2

L rotates with the shaft H owing to the worm L² and the worm wheel L³. The worm L² is normally locked against rotation in the member L by a set screw L⁴ (see Fig. 5) which when partly unscrewed permits rotation of the worm L² by the operator applying a screw driver or other tool to the outer solid end L⁵ of the shaft L⁶ of the worm L². Thus by the arrangement described, the member L can be adjusted on the shaft H so as to bring the shoulder L' into proper relation with an electric contact-maker N, which latter is in the form of a rod or pin mounted to slide in apertured lugs G³ and G⁴ formed integrally on one side of the metallic casing G containing the vibrating or induction coil F (see Figs. 3 and 5). The upper end of the contact-maker N is adapted to engage a contact F' forming part of the vibrating or induction coil F and the said contact-maker N is normally held out of contact with the contact F' by a spring O abutting with its upper end against the under side of the lug G² and resting with its lower end on a collar O' attached to the contact-maker N and adapted to rest on the top of the lug G⁴. A collar O² is secured to the lower portion of the contact-maker N and is adapted to abut against the under side of the lug G⁴ so as to limit the upward sliding movement of the contact-maker N whenever the latter is raised by the action of the shoulder L' of the member L. Now the several parts are so arranged that when the operator turns the hand wheel I² in one direction, the valve E is opened to normally open position so that the gas is applied to the burner for producing a maximum even illumination, and when the valve E reaches this normal open position the shoulder L is in engagement with the lower end of the contact-maker N. When the operator gives a further turn to the hand wheel I² then the valve E is opened beyond normal position to produce a flare of gas at the burner, and at the same time the member L is turned to cause the shoulder L' to lift the contact-maker N to engage the latter with the contact F' thereby closing the circuit for the sparking points at the burner to produce an electric spark which passes through the flaring gas thus igniting the same.

It is understood that when the contact-maker N is raised the spring O is compressed, and when the operator releases the hand wheel I² then the spring O forces the contact-maker N downward, and in doing so the contact-maker in pressing on the shoulder L' rotates the member L and with it the shaft H in a reverse direction, whereby the valve E is returned to normal open position and at the same time the circuit is broken as the contact-maker N moves out of engagement with the contact F', and

hence the electricity is shut off from the sparking points at the burner.

The contact-maker N and the spring O are protected against rain by a hood G⁵ formed integrally on one side of the cover G' and open at its lower end, the hood G⁵ inclosing the lugs G⁴, G³, the spring O and the main portion of the contact-maker N as well as the projecting end of the contact F', as will be readily understood by reference to Fig. 4. The insulated wire P for the coil F extends through a similar hood G⁶ formed integrally on the side of the cover G' opposite the one having the hood G⁵, so that the primary wire is also protected against rain. The cover G' is provided with one or more lugs G⁹ adapted to rest on the top of the coil F, so as to limit the downward movement of the cover G' and also to hold the coil F in place. Both the hoods G⁵ and G⁶ are open on the side facing the interior of the cover and the slots thus formed permit the passage of the stationary terminals or contacts. The insulated secondary wire Q is connected with the coil F.

The operation is as follows: Normally the valve E is closed, and the shoulder L' of the member L is a distance below the contact-maker N so that the latter is out of contact with the contact plate F' of the coil F and hence the latter is dormant. When it is desired to light the lamp A, the operator turns the hand wheel I² in one direction to rotate the main shaft H, whereby the valve E is opened and the member L is turned to move the shoulder L' in engagement with the lower end of the contact-maker N. This takes place at the time the valve E is open to normal position, and on further turning of the hand wheel I² the valve E is opened beyond normal position to produce a flare of gas at the burner of the lamp A and to cause the shoulder L' to lift the contact-maker N into engagement with the contact plate F' so that an electric spark is produced at the burner to ignite the gas issuing in a flare therefrom. As soon as the gas is lit, the operator releases the hand wheel I² and the several parts are now returned to normal position by the action of the spring O on the contact-maker N, that is, the latter is moved out of engagement with the contact plate F' and the member L is turned and with it the shaft H to move the valve E back into normal position to insure turning of the lamp to produce an even, uniform illumination.

From the foregoing, it will be seen that the electric spark is automatically cut off as soon as the operator releases the hand wheel I² and the valve E is automatically returned to its normal open position. If desired, the operator can still further throttle the valve E by turning the hand wheel I² in the reverse direction, it being understood that in

doing so the shaft H is turned by the gear wheels I', H', and the valve E can be closed for shutting off the gas on still further turning of the hand wheel I² in the reverse direction until the valve H has moved into closed position.

Having thus described my invention, I claim as new and desire to secure by Letters Patent:

- 10 1. The combination with an induction coil having a pair of laterally extending terminals, of a casing for said coil arranged to receive the lower part of the coil, a telescopic cover for said casing having side hoods provided with slots to permit the passage of said terminals, said side hoods covering said terminals.
- 15 2. The combination with an induction coil having a pair of laterally extending terminals, of a casing for said coil arranged to receive the lower part of the coil, a telescopic cover for said casing having side hoods provided with slots to permit the passage of said terminals, said side hoods covering said terminals, and means carried by the interior of the cover and arranged to engage the top of the coil for limiting the movement of the cover and for holding the coil in position.
- 20 3. The combination with an induction coil having a pair of laterally extending terminals, of a casing for said coil arranged to receive the lower part of the coil, a telescopic cover for said casing having side hoods provided with slots to permit the passage of said terminals, said side hoods covering said terminals.
- 25 4. The combination with an induction coil having a pair of laterally extending terminals, of a casing for said coil arranged to receive the lower part of the coil, a telescopic cover for said casing having side hoods provided with slots to permit the passage of said terminals, said side hoods covering said terminals, an inwardly extending lug carried by the interior wall of the cover and arranged to engage the top part of the coil for holding the latter in the casing and for limiting the downward movement of the cover, and a movable contact member normally covered by one of said hoods and arranged to engage one of said laterally extending contact members.
- 30 5. The combination with an induction coil having a pair of laterally extending terminals, of a casing for said coil arranged to receive the lower part of the coil, a telescopic cover for said casing having side

hoods provided with slots to permit the passage of said terminals, said side hoods covering said terminals, means carried by the interior of the cover and arranged to engage the top of the coil for limiting the movement of the cover and for holding the coil in position, and a movable contact member normally covered by one of said hoods and arranged to engage one of said laterally extending contact members.

4. The combination with an induction coil having a pair of laterally extending terminals, of a casing for said coil arranged to receive the lower part of the coil, a telescopic cover for said casing having side hoods provided with slots to permit the passage of said terminals, said side hoods covering said terminals, an inwardly extending lug carried by the interior wall of the cover and arranged to engage the top part of the coil for holding the latter in the casing and for limiting the downward movement of the cover, and a movable contact member normally covered by one of said hoods and arranged to engage one of said laterally extending contact members.

In testimony whereof I have signed my name to this specification in the presence of two subscribing witnesses.

HAROLD DUNCAN GRINNELL.
